RETRACTING TYPE THEATER CHAIR

Joseph G. Prosser and Thomas W. Prosser, Pasadena, Calif., assignors to American Seating Company, Grand Rapids, Mich., a corporation of New Jersey

Application June 26, 1946, Serial No. 679,357

8 Claims. (Cl. 155—116)

1

The present invention relates to chairs and more particularly to chairs of the retracting type for use in theaters, auditoriums and the like. This application is a continuation-in-part of our co-pending application Serial No. 679,354, filed June 26, 1946.

The primary objects of the invention are to provide an improved chair of the retracting type wherein the occupant may move the seat rearwardly in order to permit others to pass in front of him without his having to rise from the seat; to provide such a chair having a combination link and roller or link and sliding block mechanism for mounting the chair back and seat, which mechanism insures easy and comfortable forward and rearward movements and which is concealed below the level of the chair seat; to provide such a chair which when retracted occupies a minimum of space in the rear of the chair; to provide such a chair having improved means for mounting on spaced chair-supporting standards; and in general to provide such a retracting chair which is efficient in operation, reasonably economical in manufacture and attractive in appearance.

Illustrative embodiments of the invention are shown in the accompanying drawings, wherein:

Figure 1 is a perspective view of a retracting chair showing the chair seat and back in their normal, forward positions for occupancy;

Figure 2 is a perspective view similar to Figure 1 showing the chair seat and back in their retracted positions;

Figure 3 is an inside elevational view of the mounting and operating mechanism at the left-hand side of the chair, certain parts thereof being shown in vertical section taken on line 3—3 of Figure 4, and the parts of the operating mechanism being shown in their forward positions;

Figure 4 is a fragmentary front elevational view of the left-hand side of the chair;

Figure 5 is a fragmentary inside elevational view showing the parts of the operating mechanism in their rearward or retracted positions;

Figure 6 is an enlarged fragmentary sectional view taken on line 6—6 of Figure 5;

Figure 7 is a sectional view similar to Figure 6 and showing a modified construction;

Figure 8 is a view similar to Figure 3 and showing another modified form of the invention, the parts of the operating mechanism being shown in their forward positions;

Figure 9 is a view of the same with the parts of the operating mechanism being shown in their rearward or retracted positions; and

2

Figure 10 is an enlarged sectional view thereof taken on line 10—10 of Figure 8.

Referring now in detail to these drawings and referring first particularly to Figures 1 through 6, the retracting chair there shown is mounted on a frame comprising spaced, upright, chair-supporting standards 1 having inwardly projecting lugs 2 thereon provided with vertical stud-receiving slots 3, mounting members 4 having outwardly turned flanges 5 with depending, threaded studs 6 adapted to fit into the slots 3, nuts 7 threaded on the lower ends of the studs 6, and a transverse bar 8 secured as by welding to the opposite mounting members 4. The frame thus formed is of sturdy and rigid construction. If desired, members 9 of rubber, cork or other resilient material may be interposed between the flanges 5 of the mounting members and the lugs 2 on the standards for absorbing any vibration of the chair during its retracting and returning movements.

The mounting and operating mechanisms on opposite sides of the chair being of like construction, only one side is shown in Figures 3, 4 and 5 and hereinafter described. The mounting member 4 has a forwardly and upwardly extending arm 10 on the upper end of which is mounted a guide block or roller 11 thus forming guides at opposite sides of the frame. A combination seat and back support or carrier 12 is provided with a forwardly-rearwardly extending race or way 13 therein which engages in a groove 14 in the guide roller 11 (see Figure 6) and the carrier 12 is thus mounted on the chair frame for forward and rearward sliding movements.

A rear supporting member or link 15 has its lower end pivotally connected to the mounting member 4. A side plate 16 of generally triangular shape is pivotally connected to the upper end of the rear supporting link 15 and to the rearward end of the carrier 12. This side plate 16 has a forwardly and upwardly extending portion having an inclined race or way 17 therein, which engages in a groove 18 in the guide roller 11 (see Figure 6) and the side plate 16 is thus mounted for forward and rearward movement with the carrier 12 and rear supporting link 15, and for turning movement about a horizontal axis to thus vary its angular inclination. This turning movement of the side plate 16 takes place about the pivotal connection of the side plate to the rear supporting link 15, and is effected during the retracting and returning movements of the chair by the action of the guide roller 11 on the inclined way 17 of the side plate.

The chair back 19 is mounted on inwardly turned flanges 20 of the side plates 16 on opposite sides of the chair, as by means of screws 21. The chair seat 22 is provided with seat arms 23 secured to the opposite sides thereof as by means of screws 24, and the seat arms 23 are pivotally connected at 25 to the carriers 12 on opposite sides of the chair. The seat is thus movable forwardly and rearwardly with the carriers, and is also turnable about a horizontal axis so that it may be raised in order to facilitate sweeping under the chair. When in its lowered position of occupancy, the seat is supported forwardly of its axis of turning movement by means of stops 26 on the carriers 12, on which stops the seat arms 23 rest.

An equalizing strut 27 is desirably secured as by welding to the rear supporting links 15 on opposite sides of the chair so that these links are rigidly secured in assembly and move in unison, thus adding to the stability of the structure.

When the chair is retracted, the seat moves rearwardly in a substantially straight path, while the back moves rearwardly and also assumes a near-vertical position thus to minimize the space required for retraction in the rear of the chair. Forward and rearward movements of the chair are stopped by stop means comprising the ends of the ways 13 and 17 which contact the guides or rollers 11.

In Figures 1-6 inclusive the guides 11 are shown in the form of rollers, but it will be understood that stationary blocks may be employed in place of rollers. Such a block is illustrated in Figure 7 and as shown comprises laminated metal plates 28 arranged to form a groove 29 for the carrier 12 and a groove 30 for the side plate 16. These metal plates may desirably be made of "oil-less" metal which does not require periodic lubrication.

Figures 8-10 inclusive illustrate the invention in a modified construction, wherein the side plate 16 has an arcuate slot or way 11 into which extends a guide pin 18 on the carrier 12. This permits the back 19 to assume a near vertical position near the end of its rearward, retracting movement, and the arrangement replaces the forward and upward extension and way 17 on the side plate shown in Figures 1-6. As shown in Figure 10, the guide block or roller 11 of this construction has only one groove 128 for engagement by the way 113 on the carrier 112.

It will thus be seen that a retracting chair has been provided having a novel combination of links and rollers in which the mounting and operating mechanism is, for the most part, located out of sight below the seat level, and which mechanism is arranged for easy and comfortable forward-rearward movements of the chair. While but several specific embodiments of the chair have been herein shown and described, it will be understood that numerous details of the constructions shown may be altered or omitted without departing from the spirit of the invention as the same is defined by the following claims, wherein the word "frame" is to be construed broadly enough to include either a unitary assembly or a pair of spaced chair standards whose only rigid connection is the floor upon which such pair of standards is installed.

We claim:

1. In a chair, a frame having guides at opposite sides thereof, carriers having ways engaging the guides for forward and rearward movement thereon, a chair seat mounted on the carriers

and movable forwardly and rearwardly therewith, side plates pivotally connected to said carriers respectively and having forwardly-upwardly inclined ways engaging the guides for forward-rearward rocking movement thereon, rear supporting links having their lower ends pivotally associated with the frame and their upper ends pivotally connected to the side plates respectively, a chair back mounted on the side plates, and stop means for limiting the forward and rearward movements of the carriers.

5 2. In a chair, a frame having guides at opposite sides thereof, carriers having ways engaging the guides for forward and rearward movement thereon, a chair seat mounted on the carriers and movable forwardly and rearwardly therewith, side plates pivotally connected to said carriers respectively and having forwardly-upwardly inclined ways engaging the guides for forward-rearward rocking movement thereon, rear supporting links having their lower ends pivotally associated with the frame and their upper ends pivotally connected to the side plates respectively, a chair back mounted on the side plates, a strut connecting the rear supporting links in rigid assembly, and stop means for limiting the forward and rearward movements of the carriers.

20 3. In a chair, a frame having guides at opposite sides thereof, carriers having ways engaging the guides for forward and rearward movement thereon, a chair seat pivotally mounted on the carriers movable forwardly and rearwardly with the carriers and turnable about a horizontal axis, means on the carriers for supporting the seat in a lowered position for occupancy, side plates pivotally connected to said carriers respectively and having forwardly-upwardly inclined ways engaging the guides for forward-rearward rocking movement thereon, rear supporting links having their lower ends pivotally connected to the frame and their upper ends pivotally connected to the side plates respectively, a chair back mounted on the side plates, and stop means for limiting the forward and rearward movements of the carriers.

30 4. In a chair, a frame having rollers turnably mounted at opposite sides thereof, carriers having ways engaging the rollers for forward and rearward movement thereon, a chair seat mounted on the carriers, and movable forwardly and rearwardly therewith, side plates pivotally connected to said carriers respectively and having forwardly-upwardly inclined ways engaging the rollers for forward-rearward rocking movement thereon, rear supporting links having their lower ends pivotally connected to the frame and their upper ends pivotally connected to the side plates respectively, a chair back mounted on the side plates, and stop means for limiting the forward and rearward movements of the carriers.

40 5. In a chair, a frame having rollers turnably mounted at opposite sides thereof, carriers having enclosed ways engaging the rollers for forward and rearward movement thereon, a chair seat mounted on the carriers and movable forwardly and rearwardly therewith, side plates pivotally connected to said carriers respectively and having forwardly-upwardly inclined enclosed ways engaging the rollers for forward-rearward rocking movement thereon, rear supporting links having their lower ends pivotally associated with the frame and their upper ends pivotally connected to the side plates respectively, and a chair back mounted on the side plates, the forward and rearward ends of the enclosed ways on said carriers and said side plates being adapted to contact said

rollers to limit the rearward and forward movements respectively of said carriers and said side plates.

6. In a chair, a frame having rollers turnably mounted at opposite sides thereof each of said rollers having two peripheral grooves therein, carriers each having an enclosed way engaging in one groove of a roller for forward and rearward movement thereon, a chair seat mounted on the carriers and movable forwardly and rearwardly therewith, side plates each pivotally connected to a carrier and each having a forwardly-upwardly inclined enclosed way engaging in the other groove of the adjacent roller for forward-rearward rocking movement thereon, rear supporting links having their lower ends pivotally connected to the frame and their upper ends pivotally connected to the side plates respectively, and a chair back mounted on the side plates, the forward and rearward ends of the enclosed ways on said carriers and said side plates being adapted to contact said rollers to limit the rearward and forward movements respectively of said carriers and said side plates.

7. In a chair: spaced, upright chair-supporting standards; mounting members secured to the standards respectively below the seat level; rollers on the upper ends of the mounting members turnable about fixed horizontal axes; carriers having ways engaging the rollers for forward and rearward movement thereon; a chair seat mounted on the carriers and movable forwardly and rearwardly therewith; a chair back having at its opposite sides forwardly extending side plates pivotally connected at their lower ends to the rearward ends of said carriers respectively, said side plates and chair back being movable forwardly and rearwardly with the carriers and turnable about a horizontal axis relative thereto; supporting members having their lower ends pivotally connected to the mounting members respectively below and rearwardly of said rollers; said supporting members extending above the seat level and having their upper ends pivotally connected to the side plates above the pivotal connections of the side plates to the carriers; and stop means for

limiting the forward and rearward movements of the chair seat and chair back.

8. In a chair: spaced, upright chair-supporting standards; mounting members secured to the standards respectively below the seat level; rollers on the upper ends of the mounting members turnable about fixed horizontal axes; carriers having ways engaging the rollers for forward and rearward movement thereon; a chair seat mounted on the carriers and movable forwardly and rearwardly therewith; a chair back having at its opposite sides forwardly extending side plates pivotally connected at their lower ends to the rearward ends of said carriers respectively, said side plates and chair back being movable forwardly and rearwardly with the carriers and turnable about a horizontal axis relative thereto; supporting members having their lower ends pivotally connected to the mounting members respectively below and rearwardly of said rollers, said supporting members extending above the seat level and having their upper ends pivotally connected to the side plates above the pivotal connections of the side plates to the carriers; means operatively connecting the carriers with the side plates whereby the angle between the back and seat is decreased during rearward movement thereof and increased during forward movement thereof; and stop means for limiting the forward and rearward movements of the chair seat and chair back.
